Elemin J. Ney, of Lowell, Mass.
Assignor to

Lowell Manufacturing Company, of Lowell Mass.
Letters Patent No. 1817 - Dated Sept. 1st 1863.
Design for a Carpet Pattern.

The schedule referred to in these Letters Patent and making part of the same,

To all whom it may concern:

Be it known, that I, Elemin J. Ney, of Lowell in the County of Middlesex and State of Massachusetts, have originated and designed a new Pattern for Carpets or other fabrics, of which the following is a full, clear and exact description, reference being had to the accompanying drawings, making part of this specification.

In corner 1 is one fourth of a plain figure supporting a small rosette and resting on the large dotted figure A.

The ground on which rests fig. A, is enclosed by the frame 2.

In corner 3 is one fourth of a small rosette surrounded by sprigs resting on a ground enclosed by a scalloped frame. The figures and surroundings of corners 4 and 5 are similar to those of corners 1 and 3 respectively. In the centre is a group composed of two large flowers, sprigs and light mottled leaves.

6 and 7 are small oblong blocks.

8, 9 are grounds of regular work partially surrounded by the bands 9, 9.

10, 10. are grounds of mottled work partially surrounded by the bands 11, 11.

The colors employed for the different portions of the design, may be varied to suit the taste and wish of the manufacturer.
